UNITED STATES PATENT OFFICE.

LEWIS E. ZERBE, OF MONETA, CALIFORNIA, ASSIGNOR TO UNION TOOL COMPANY, OF TORRANCE, CALIFORNIA, A CORPORATION OF CALIFORNIA.

CASING ELEVATOR.

Application filed March 20, 1922. Serial No. 545,102.

To all whom it may concern:

Be it known that I, LEWIS E. ZERBE, a citizen of the United States, residing at Moneta, in the county of Los Angeles and State of California, have invented a new and useful Casing Elevator, of which the following is a specification.

This invention relates to casing elevators and is particularly directed to an elevator of the type generally used for raising, lowering or supporting well casings, sucker rods, and pump tubing.

An object of the invention is to provide a two-part hinged unit elevator contoured to define a vertical bore having a minimum diameter adjacent the upper surface of the elevator with the remainder of the bore of larger diameter to provide clearance permitting a tilting of the elevator while engaged upon a well casing and to permit a closing of the gate while the elevator is engaged in a tilted position upon a well casing.

A further object is to contour the inner surfaces of the bore so as to require a minimum amount of machining in the manufacture of the elevator.

Various other objects and advantages will be more fully apparent from the following description of the accompanying drawings which form a part of this disclosure, and which illustrate a preferred form of embodiment of the invention.

Of the drawings—

Figure 1 is a plan view of the elevator; and

Fig. 2 is a section on line 2—2 of Fig. 1, showing the elevator engaging a well casing.

The general type of elevator herein illustrated is the same as that illustrated in the patent to Double & Youngken, No. 1,358,943, issued November 16, 1920, to which reference may be had for detailed illustration and description of parts which are not herein shown and described.

The body portion of the elevator comprises a substantially U-shaped casting 1, the medial concave inner surface of which forms an approximate half circle and is adapted to engage the casing or rod to which the elevator is applied. Diametrically opposed ears 2—2 extend outwardly from the body 1 and are provided with transverse orifices 3—3 to receive the ordinary and well known bails by which the elevator is supported.

The gate 4 is hinged to the body at 5 and its free end is engaged by a latch 6 carried by the body 1, to maintain the gate closed, said latch being operable to release the gate and permit it to be swung outwardly so that the elevator may be engaged with a well casing.

The inner medial surface of the gate is concaved to conform to the concave surface of the body and when the gate is closed both surfaces register to form a vertical bore adapted to receive the object with which the elevator is engaged.

In elevators of this general type, and especially in the structure disclosed in the previously mentioned patent, the walls of the bore closely embrace the casing, tubing or rod, at both ends of the bore and consequently allow a closing of the gate only when the elevator is positioned with the axis of the bore accurately aligned with the axis of the casing, tubing or rod to be engaged.

Such an accurate manipulation of elevators of this class is undesirable especially on account of the time required to engage the elevator upon the object to be handled.

In the present invention the concave surfaces of the gate 4 and of the body 1 are each provided with lateral flanges 7 extending downwardly a relatively short distance from the top surface of the elevator to define a bore of minimum diameter, the remaining portion of the bore being of larger diameter so as to provide sufficient clearance, as at 8, to permit a slight relative tilting of the casing 9 and the elevator, it being understood that the minimum diameter of the bore is slightly greater than the outside diameter of the casing so as to permit such relative tilting.

By so providing a bore which is enlarged from the lower surface of the elevator upwardly throughout a major portion of its length, I am able to fully close the gate 4 while the elevator is in a tilted position upon the casing so that instead of having to first accurately align the elevator on the casing the operator can apply the elevator while in a position of approximate alignment. This results in a great saving of time in the manipulation of the elevator and a greater degree of certainty in the latching of the gate.

A further advantage of the present construction resides in the substantial reduction in the length of that portion of the bore

which it is necessary to machine, it being evident that only the short flanges 7 require machining, the remainder or that portion of larger diameter being cast into the parts.

5 While the form of device herein shown and described is a preferred form, it is not intended to limit the invention to the precise details thereof, for it is susceptible of embodiment in various forms, all coming within the scope of the following claim.

I claim:

A well casing elevator comprising a body and a gate hingedly united and having complementary concave inner surfaces operative,

when the gate is closed, to provide a vertical bore, and a latch for maintaining the gate closed and operable to release the gate, said concave surfaces having complementary flanges extending downwardly a relatively short distance from the top surface of the elevator to define a smooth-surfaced interior bore diameter and to provide diametrical clearance below said flanges to permit tilting of the elevator while engaged with a well casing.

Signed at Torrance, California, this 11th day of March, 1922.

LEWIS E. ZERBE.
